J. A. COSTELLO

CLOSURE FOR FLUID CONDUCTING MEMBERS

Filed March 30, 1926

Inventor:
Joseph A. Costello

By *Charles Naser*
his Attorney.

UNITED STATES PATENT OFFICE.

JOSEPH A. COSTELLO, OF CLEVELAND, OHIO, ASSIGNOR TO THE CLEVELAND BRASS MANUFACTURING COMPANY, OF CLEVELAND, OHIO, A CORPORATION OF OHIO.

CLOSURE FOR FLUID-CONDUCTING MEMBERS.

Application filed March 30, 1926. Serial No. 98,632.

This invention relates to improvements in closures for fluid-conducting members, and more especially to a closure which comprises an internally screw-threaded rigid metal ring having an annular end face at one end and screwable onto a fluid-conducting member adapted to receive or discharge fluid at its end adjacent said face and also comprises a rigid metal cover arranged to close said end of said ring as well as axially shiftable, when it is loose in relation to said face, into fluid-tight engagement with said face during the required rotation of the cover and adapted to be locked in said engagement with said face so as to prevent the ingress of foreign matter into, or to prevent leakage or escape of fluid from, said fluid-conducting member while the latter is not being employed in conducting fluid.

One object of this invention is to render a closure of the character indicated highly practical, convenient and simple and durable in construction.

The hereinbefore mentioned ring, when it has been screwed onto the hereinbefore mentioned fluid-conducting member, is not detached from said fluid-conducting member unless said fluid-conducting member requires replacement by a longer or shorter fluid-conducting member, and another object of my invention is to render the hereinbefore mentioned cover readily applicable to and removable from said ring without resulting in disengagement of said ring from the connected fluid-conducting member after said ring has been applied to said fluid-conducting member.

With these objects in view, and to attain any other objects hereinafter appearing, this invention consists in certain meritorious features of construction, and combinations and relative arrangements of parts, herein-after described in this specification, pointed out in the claims, and illustrated in the accompanying drawings.

In said drawings, Figure 1 is a side view of a vertical portion of a fluid-conducting member provided with a closure embodying my invention. Fig. 2 is a horizontal section taken along line 2-2 in Fig. 1. Fig. 3 is a central vertical section taken along line 3-3 in Fig. 2. Fig. 4 is a vertical section taken along the curved line 4-4 in Fig. 2. Fig. 5 is a section taken along line 5-5 in Fig. 4.

Referring to said drawings, A indicates a

vertical fluid-receiving or fluid-discharging end portion of a tubular member such, for instance, as the spout of a faucet, or the inlet-forming member of a tank or reservoir to which fluid is to be supplied.

My improved closure comprises an internally screw-threaded rigid metal ring B which (see Fig. 3) is shown screwed onto the fluid-conducting member A from below. The ring B extends below the member A and is provided, at its lower or outer end, with an annular internal flange 8 shown arranged under and spaced from said member A and forming a seat for a washer 9 shown interposed between said flange and the lower end of said member A. The fluid-conducting member A is generally but not necessarily provided with a valve not shown, and the washer 9 is, of course, quite necessary in introducing fluid under considerable pressure at the lower end of and into said member A, but obviously said washer may be dispensed with when the screw-threaded connection between the members A and B is adequate against leakage of fluid between said members. The bottom or outer side of the flange 8 constitutes a substantially horizontal annular end face 10 formed at the lower or outer end of the ring B. It will be observed, therefore, that the ring B has an annular end face 10 at one end, and I would here remark that said ring has two external flanges 12 arranged at opposite sides respectively of the ring and spaced from said face in the direction of the opposite end of the ring and also spaced and extending circumferentially of the ring, as shown in Figs. 1 and 2.

My improved closure also comprises a rotatable cover C shown arranged horizontally and closing the lower or outer end of the ring B and held in its closed position as will hereinafter appear. The cover C (see Figs. 2 and 3) comprises an annular gasket 13 seated on a substantially horizontal annular surface 14 formed on the inner side of the cover. The end face 10 of the ring B and the seat 14 are concentric in relation to the axis of the cover C, and said gasket 13 is shown as having an external diameter which measures more than the external diameter of said face and somewhat less than the external diameter of said seat.

The ring B (see Figs. 1 and 3) preferably has a sloping circumferential surface 15 be-

tween its end face 10 and the flange 12, and said ring is gradually reduced in external diameter toward said face from said flanges.

The cover C comprises an annular portion 16 which surrounds the gasket 13 and is substantially concentric in relation to the axis of the cover and spaced from said flanges in the direction in which the end face 10 of the ring B faces, and said portion of the cover 10 (see Figs. 2 and 3) has an internal annular member 17 extending circumferentially of said ring B between said face and the flanges 12 and spaced from said flanges and from the sloping surface 15 and overlapping the gasket 13. Preferably the annular portion 16 of the cover C is spaced from the under side of the flanges 12 of the ring B and from said ring between the end face 10 of the ring and said flanges to an extent somewhat greater than required to permit readjustment of the cover in relation to said face for taking up wear on the gasket 13 as well as to render the cover axially shiftable toward the upper or inner end of the ring B when the gasket is loose in relation to said face.

Each flange 12 of the ring B (see Figs. 1 and 3) has a sloping top side or surface 18 facing upwardly or toward the inner end 30 and extending endwise and circumferentially of the ring so that one end of said sloping surface is spaced farther than its other end from the end face 10 of the ring, and said flange has a substantially vertical surface 19 formed at the first-mentioned end of said sloping surface and extending from the under side of the flange to said sloping surface as shown in Figs. 4 and 5.

The annular portion 16 of the cover (see Figs. 1 and 2) is shown as having two outward enlargements 20 arranged at opposite sides respectively and extending circumferentially of the axis of the cover and also extending opposite the under side and endwise of and spaced from opposite flanges 12 respectively of the ring B, and each cover-enlargement 20 has a lug 21 spaced endwise of the flange 12 adjacent said enlargement from the surface 19 of said flange in the direction of the lower end of the sloping surface 18 of the flange.

Each lug 21 extends opposite the circumferential surface of the flange 12 adjacent said lug and has a rigid member 22 overlapping the sloping surface 18 of said flange, and the cover-enlargement 20 comprising said lug extends from the lugs circumferentially of the axis of the cover in the direction of and beyond the surface 19 of said flange, as shown in Fig. 2. It will be observed therefore that the members 22 of the lugs 21 of the cover and the sloping surfaces 18 on the flanges 12 of the ring B are arranged to constitute means whereby, when the cover is loose in relation to the end face

10 of said ring, rotation of the cover to the extent required in the direction in which the surfaces 19 of the flanges 12 face results in axially shifting the cover into fluid-tight engagement, at its gasket 13, with said end 70 face 10 of said ring.

Each enlargement 20 of the annular portion 16 of the cover has a series of holes 23 which are substantially parallel with and spaced circumferentially of the axis of and extend through the cover, and said series of holes is preferably concentric in relation to said axis and extends endwise of and opposite the adjacent flange 12, and the holes of the series of holes adjacent one of the flanges 12 are staggered in relation to the holes of the series of holes adjacent the other of said flanges.

It will not only be observed that the surfaces 19 of the flanges 12 face in the direction in which the cover is rotated for effecting axial movement of the cover into fluid-tight engagement with the end face 10 of the ring B but that the relative arrangement of said flanges and both hereinbefore mentioned series of holes 23 is such that one hole of one series of holes, after the required rotation of the cover for effecting said fluid-tight engagement of the cover with said face of said ring, fully registers with the space next opposite the surface 19 of the flange adjacent the last-mentioned series of holes, as shown in Figs. 2, 4 and 5, to permit the extension of the bow 24 of a padlock D through said hole and opposite and into close proximity to the last-mentioned surface so that said bow 24 and said surface 19 constitute means for preventing rotation of the cover in the opposite direction and independently of said ring and thereby locking the cover against becoming loose in relation to the end face 10 of said ring.

Preferably the holes of the two series of holes 23 are uniform in diameter, and it will be observed, as shown in Fig. 2, that the holes of both series of holes are spaced equidistantly circumferentially of the axis of the cover, and that the arrangement of the holes of one series of holes in relation to the holes of the other series of holes is such that when one hole of one series of holes fully registers with the space opposite the surface 19 of the flange 12 adjacent the last-mentioned holes, after the required actuation of the cover into fluid-tight engagement with the end face 10 of the ring B preparatory to the application of the padlock at said hole, substantially one half of a hole of the series of holes adjacent the other flange 12 registers with the space opposite the surface 19 of the last-mentioned flange so that little movement of the cover, for taking up wear on the gasket 13, is required to fully register the last-mentioned hole with the last-mentioned space as re- 130

quired to permit the application of the padlock at said last-mentioned hole.

I would also remark that the cover is provided, at its outer side, with flanges or rigid members 25 extending substantially radially of the cover from the annular portion 16 to the central portion of the cover and spaced circumferentially of the axis of the cover, and said members 25 not only reinforce the cover but are arranged to constitute handle-forming means for convenience in manipulating the cover.

My improved closure for a fluid-conducting member has been found more especially useful when applied to a fluid-conducting member constituting the fluid-inlet or fluid-outlet of a tank or receptacle which is employed in retailing, collecting or storing oil or other fluid, and adapted to be carried by trucks or vehicles on public highways, because said closure, when thus applied, effectively excludes dust and dirt from said inlet or outlet without interfering with a convenient and quick manipulation of the cover independently of the ring B. It will be observed that the internal flange 8 of the ring B clamps the washer 9 to the lower end of the fluid-conducting member A, that the frictional engagement of said washer with said fluid-conducting member and with said flange and the friction between the mutually engaging screw-threads of said fluid-conducting member and ring oppose the rotation of said ring with the cover C during the rotation of the said cover in the direction required to loosen it at the lugs 22 in relation to the flanges 12 of said ring after removal of the padlock D, that said ring has a long enough screw-threaded connection with said fluid-conducting member to require quite a number of complete rotations of said ring about said fluid-conducting member to unscrew the ring from said fluid-conducting member, and that in any event said ring is tight enough in relation to said fluid-conducting member to prevent corresponding rotation of said ring with the cover C when said cover is suddenly rotated only a very small fraction of an inch in the direction required to loosen the cover in relation to said flanges of said ring, and said cover during said slight rotation thereof will have been positively loosened in relation to said ring without material if any movement of the ring. I would here remark that, in the absence of the application of the padlock D as hereinbefore described, vibration of the fluid-conducting member B and attached closure is liable to result in loosening the cover C at its lugs 22 in relation to the sloping surfaces 18 of the flanges 12 of the ring B and permit rotation of said cover independently of the ring in the direction that would permit loosening of said cover in relation to said ring, and it will be observed

therefore that not unimportant is the provision made in the hereinbefore described construction for the application of a padlock because the bow of a padlock applied as hereinbefore described constitutes a highly suitable member for cooperating with one of the flanges 12 of said ring in positively preventing said rotation of said cover when the cover is in clamping relation to said ring.

What I claim is:

1. A closure of the character indicated comprising an internally screw-threaded ring which has an annular end face at one end and circumferentially spaced external flanges and is screwable onto a fluid-conducting member adapted to receive or discharge fluid at its end adjacent said face, and a rotatable cover which is arranged to close the aforesaid end of said ring and has holes substantially parallel with and spaced circumferentially of the axis of and extending through the cover, said cover and aforesaid flanges having means whereby the required rotation of the cover, when the cover is loose in relation to the aforesaid face, results in shifting the cover axially into fluid-tight engagement with said face, each of the aforesaid flanges having a surface facing in the direction of said rotation of the cover, and one hole of the aforesaid holes registering, after said rotation of the cover, with the space next opposite said surface of one of said flanges to permit the extension of the bow of a padlock through said hole and opposite and into close proximity to said surface.

2. A closure of the character indicated comprising an internally screw-threaded ring which has an annular end face at one end and two circumferentially extending external flanges arranged at opposite sides respectively of the ring, and a rotatable cover arranged to close said end of said ring and having a series of holes adjacent one of said flanges and another series of holes adjacent the other of said flanges, said holes extending through the cover, each series of holes being arranged circumferentially of the axis of the cover with the holes of one series staggered in relation to the holes of the other series, the cover and aforesaid flanges having means whereby the required rotation of the cover, when the cover is loose in relation to the aforesaid face, results in shifting of the cover into fluid-tight engagement with said face, said flanges each having a surface facing in the direction of said rotation of the cover, and a hole of one of the aforesaid series of holes registering, after said rotation of the cover, with the space opposite said surface of one of said flanges.

3. A closure of the character indicated comprising an internally screw-threaded ring having an annular end face at one end and two circumferentially extending

external flanges arranged at opposite sides respectively of the ring, and a rotatable cover arranged to close said end of said ring and having an annular portion which is substantially concentric in relation to the axis of the cover and spaced from said flanges in the direction of the aforesaid face and also spaced from said ring between said face and said flanges and has a series 10 of holes adjacent one of said flanges and another series of holes adjacent the other of said flanges, said holes being spaced circumferentially of the axis of and extending through the cover, said annular portion of 15 the cover and the aforesaid flanges having means whereby the required rotation of the cover, when the cover is loose in relation to said face, results in shifting the cover into fluid-tight engagement with said face, said flanges each having a surface facing in the direction of said rotation of the cover, and a hole in one of the aforesaid enlargements of the aforesaid annular portion of the cover registering, after said rotation of the cover, with the space opposite the aforesaid surface of 20 one of said flanges.

4. A closure of the character indicated comprising an internally screw-threaded ring which has an annular end face at one end and external flanges spaced and extending circumferentially of the ring, and a rotatable cover arranged to close said end of said ring and having an annular portion which is substantially concentric in relation to the axis of the cover and arranged 25 between the outer side of the cover and said flanges and spaced from said flanges and has outward enlargements extending opposite and endwise of the different flanges respectively and each having a series of 30 holes which extend through the cover, said series of holes extending circumferentially of said axis, the cover and the aforesaid flanges having means whereby the required 35

rotation of the cover, when the cover is loose in relation to the aforesaid face, results in shifting the cover into fluid-tight engagement with said face, said flanges each having a surface facing in the direction of 40 said rotation of the cover, and a hole in one of the aforesaid enlargements of the aforesaid annular portion of the cover registering, after said rotation of the cover, with the space opposite the aforesaid surface of one of said flanges.

5. A closure of the character indicated comprising an internally screw-threaded ring which has an annular end face at one end and two circumferentially extending external flanges arranged at opposite sides respectively of the ring, and a rotatable cover arranged to close said end of said ring and having a series of holes adjacent one 50 of said flanges and another series of holes adjacent the other of said flanges, the holes of both series extending through the cover and being substantially uniform in diameter and correspondingly spaced circumferentially of the axis of the cover, said cover and said flanges having means whereby the required rotation of the cover, when the 55 cover is loose in relation to the aforesaid face, results in shifting the cover into fluid-tight engagement with said face, said flanges each having a surface facing in the direction of 60 said rotation of the cover, and a hole in one of the aforesaid enlargements of the aforesaid annular portion of the cover registering, after said rotation of the cover, with the space opposite the aforesaid surface of one of said flanges.

In testimony whereof, I sign the foregoing specification.

JOSEPH A. COSTELLO.
